RADIO-FREQUENCY OPERATED RECEIVING
SYSTEM CONSUMING ZERO STANDBY
POWERPhillip W. Russell and Joseph L. Harmon,
Cleveland Heights, Ohio

Application July 3, 1948, Serial No. 36,914

3 Claims. (Cl. 315—156)

1

The present invention relates to radio-frequency-operated receiving systems embodying relay means actuated upon by signals of predetermined carrier frequency which effect remote control of the relay means and power circuit means governed and controlled thereby.

The primary object of the invention is the provision of a radio-frequency-operated receiving system including means adapted to successively modulate, step up and rectify signals of a received, predetermined carrier frequency, glow-discharge tube means adapted to be activated by thus changed signals, and relay circuit means controlled by the glow-discharge tube means to control actuation of the relay of the relay circuit means and power circuit means governed and controlled by such relay.

Another object of the invention is the provision of a radio-frequency-operated receiving system including means adapted to successively modulate, step up and rectify the signals of a received, predetermined carrier frequency, a glow-discharge-tube-controlled circuit with a glow-discharge tube of the three-element, cold-cathode type having its grid potentialized by the received, modulated, stepped-up and rectified signals, and a relay circuit controlled by the glow-discharge tube and adapted to effect controlled actuation of the relay of the relay circuit and power circuit means governed and controlled by such relay. A radio-frequency-operated receiving system of the type described above practically eliminates all standby power for the system by the use of crystal detectors and transformer means in combination with cold cathode type glow-discharge tube means, and thus offers reliability and economy together with sufficient sensibility to permit proper operation of the system at reasonably long distances.

A further object of the invention, therefore, is the provision of a radio-frequency-operated receiving system including a crystal detector for modulating received radio frequency signals, transformer means for stepping up the modulated radio frequency signals, a rectifying circuit for rectifying the modulated, stepped up radio frequency signals, including the grid of a three-element, cold-cathode type glow-discharge tube, and a relay control circuit including the glow-discharge tube and activated by firing of the glow-discharge tube caused by changes in its grid potential.

The above and other incidental and additional objects and novel features of combination and relations of parts by which the objects in view

2

have been attained will appear and are set forth in detail in the course of the following specification.

The drawing accompanying and forming part of the specification illustrates in diagrammatic form a practical embodiment of the invention, but it will be apparent as the specification proceeds that changes and modifications may be made in various ways without departing from the true spirit and broad scope of the invention.

10 In the drawing:

The single figure is a diagrammatic showing of a simplified radio circuit illustrating the present invention, utilizing modulated, stepped-up and rectified radio-frequency signals for control of a glow-discharge tube which activates and controls the relay of a relay-controlled power circuit.

Referring now in detail to the diagrammatic showing of the radio circuit, reference numeral 2 denotes the usual antenna of any of the well known types such as the single strand antenna or others well known in the art, which is suitably grounded through the primary radio frequency coil 3 of the input transformer 4. This input transformer includes a secondary radio-frequency coil 5 grounded and tuned by a variable condenser 6, which is connected in parallel circuit to coil 5. The elements thus far described constitute a simple form of a tuned radio-frequency circuit for which any of the well known tuned circuits may be substituted. Condenser 6 and coil 5 have their one ends connected to one side of a crystal detector or demodulator 7 which has its other side connected to a fixed condenser 8 and one side of the primary coil 9 of a voltage step-up transformer 10. The other side of condenser 8 is connected to ground and to the other side of coil 9.

Step-up transformer 10 has one end of its secondary coil 11 connected to a crystal detector or demodulator 12 and the other end of such coil connected to one of the stationary resistance coils of a potentiometer 14 which is connected with a power line 15 by means of lead wires 16 and 17.

45 The rectifier 12 has its free side connected to the grid 18 of a three-element, cold-cathode type glow discharge tube 19 which has its cathode 20 connected by the lead wire 17 to power line 15 and its plate 21 connected to the one plate member of a fixed condenser 22, the other member of which is connected to the lead wire 16. Fixed condenser 22 is bridged by the coil member 23 of a relay 24, the switch member 25 of which controls a power circuit 26 directly connected with the power line 15. This power

circuit includes a plug member 27 for connection of the device to be actuated or driven with power circuit 26. When a radio-carrier-frequency signal is received in the antenna 2 and passed through coil 3, a correspondent current will be set up in the tuned secondary coil 5 and in the circuit, including the crystal detector or demodulator 7 and primary coil 9. This current which is a modulated frequency of the received carrier frequency sets up a correspondent current in a circuit including the secondary coil 11 of step-up transformer 10, demodulator 12, grid 18 of glow-discharge tube 19 and the fixed resistance coils of potentiometer 14. The last-named, correspondent current, a rectified current, stepped up in voltage by the step-up transformer 10, changes the bias of grid 18 and thereby effects firing of the glow-discharge tube 19, thus closing a relay operating circuit which is fed by the power line 15 and includes the cold-cathode type glow-discharge tube 19 and the coil member 23 of the relay 24. The current flow through coil member 23 effects closing of the relay which then closes the power circuit 26 including the relay switch member 25 and the plug member 27 to be used for connecting a device to be actuated upon with said power circuit.

The three-element, cold-cathode type glow-discharge tube 19 is preferably a gas triode glow-discharge tube which will fire and cease to fire at a grid potential difference of one half to one volt and will operate on a current consumption of two microamperes.

The exemplified diagrammatic showing of the simplified radio circuit illustrating the invention has given highly satisfactory results with a carrier frequency of 50 megacycles and a modulation frequency of 400 cycles obtained by using a demodulator 7, a silicon crystal diode #IN21B, detector or demodulator 12, a germanium crystal diode #IN34, transformer 10, an iron core inter-state step-up transformer with a ratio 1/6, glow discharge tube 19, a gas triode glow discharge type #IC21, and a supply voltage 15 of 115 volts, 60 cycles. The potentiometer 14 used included stationary resistor coils of 300,000 and 15,000 ohms and a variable resistor coil of 15,000 ohms. Condensers used had the following capacities:

Variable condenser 3=0-30 μ uf.
Variable condenser 5=0-50 μ uf.
Condenser 8=100 μ uf.
Condenser 22=4 μ f.

and the relay used was an advance type relay #860 with 10,000 ohms resistance.

A radio frequency operated receiving system of the type described above achieves the same reliability and economy offered by direct wire circuits as all standby power is fully eliminated

and as the system has sufficient sensitivity at reasonably long distances.

Having thus described our invention, what we claim is:

- 5 1. In a standby power eliminating, radio-frequency-operated receiving system, a no-power-consuming crystal detector circuit, a voltage step-up transformer coupling said circuits with each other and a circuit including a three-element cold cathode type gas discharge tube having its grid electrically connected with the second crystal detector circuit to control firing of said gas discharge tube by signals received and stepped up by the receiving system.
- 10 15 2. A standby power-eliminating radio-frequency-operated receiving system as described in claim 1, wherein said three-element glow-discharge tube consists of a gas triode discharge tube firing and ceasing to fire at a grid potential difference from one half to one volt and operating on a current consumption of about two microamperes.
- 20 25 3. In a standby power eliminating, radio-frequency-operated receiving system, a tuned, no-power-consuming, radio-frequency-receiving circuit, a first no-power-consuming radio-frequency-demodulating circuit connected to said receiving circuit and including a crystal detector, a second no-power-consuming demodulating circuit also including a crystal detector, a voltage step-up transformer coupling the first demodulating circuit with the second demodulating circuit and a circuit including a three-element, glow-discharge tube having a grid electrically connected with the second demodulating circuit to control firing of said glow-discharge tube and energizing of the circuit including said glow discharge tube.
